(57) **CLAIM**

The ornamental design for a lighted mirror, as shown and described.

DESCRIPTION

FIG. 1 is a perspective view of a lighted mirror, showing our new design;

FIG. 2 is a front view thereof;

FIG. 3 is a left side view and a right side view thereof;

FIG. 4 is a top view and a bottom view thereof;

FIG. 5 is a back view thereof;

FIG. 6 is a perspective view of a second embodiment of a lighted mirror, showing our new design;

FIG. 7 is a front view thereof;

FIG. 8 is a left side view and a right side view thereof;

FIG. 9 is a top view and a bottom view thereof; and,

FIG. 10 is a back view thereof.

1 Claim, 6 Drawing Sheets

Fig.1.
